US0D1038501S

(12) **United States Design Patent** (10) **Patent No.:** **US D1,038,501 S**
(45) **Date of Patent:** ** Aug. 6, 2024

(54) **AEROSOL GENERATOR**

- (71) Applicant: **Nicoventures Trading Limited**,
London (GB)
- (72) Inventors: **Jared Aller**, Winston-Salem, NC (US);
Ali Gallaher, London (GB); **Kang Min Kim**, London (GB); **Andy Vernall**, London (GB); **Jonathon Lister**, London (GB)
- (73) Assignee: **NICOVENTURES TRADING LIMITED**, London (GB)

(**) Term: **15 Years**

(21) Appl. No.: **29/837,344**

(22) Filed: **May 4, 2022**

(30) **Foreign Application Priority Data**

(57) **CLAIM**

We claim the ornamental design for an aerosol generator, as shown and described.

DESCRIPTION

FIG. 1 is a top front perspective view of an aerosol generator showing the claimed design;

FIG. 2 is a top perspective view thereof;

FIG. 3 is a bottom rear perspective view thereof;

FIG. 4 is a top view thereof;

FIG. 5 is a bottom view thereof;

FIG. 6 is a front view thereof;

FIG. 7 is a rear view thereof;

FIG. 8 is a left view thereof; and,

FIG. 9 is a right view thereof.

The broken lines in the drawings illustrate portions of the aerosol generator that form no part of the claimed design. The dot-dash broken lines in the drawings illustrate boundaries of the aerosol generator that form no part of the claimed design.
